APPARATUS FOR APPLYING BINDING MATERIALS

Daniel C. Drill, Wabash, and Charles L. White-nack, Elwood, Ind., and Jesse H. Gregory, Wheaton, Ill., assignors to American Rock Wool Corporation, Wabash, Ind., a corporation of Indiana.

Original application July 5, 1935, Serial No. 29,942. Divided and this application June 25, 1938, Serial No. 215,798.

3 Claims. (Cl. 49—1)

Our invention generally relates to apparatus for applying binding materials in the production of felted mineral wool strips, blankets, and batts, hereinafter, for convenience, termed "batts."

5 This application is a division of our original application, Serial Number 29,942, filed July 5, 1935, and issued July 26, 1938, as U. S. Patent No. 2,124,768.

In order that a more perfect understanding of 10 our invention may be had, a brief description of the methods usually followed in manufacturing mineral wool batts will be given.

Mineral wool is made of wool rock, or slag, to 15 which a special fusing rock may be added. The raw material is mixed with coke in a cupola or furnace and heated to a temperature of, say, approximately 3,000° F., at which the material becomes molten and is permitted to pour out in a continuous stream of approximately one-half 20 inch in diameter. This stream is subjected to a blast of steam, of sufficient power to shred the molten material into fibers. The blast is directed into an adjacent blow chamber which is preferably provided with a movable base or conveyor. 25 The length of the settling chamber is sufficient to permit the blast to leave the fibers in suspension, swirling in the heated vapors and gases of the chamber, above the conveyor.

These fibers are inherently tacky and rapidly 30 combine in myriads of loose, fluffy bunches which slowly settle on the moving base of the conveyor to become incorporated with the forming batt. While the fibers are naturally tacky, they do not 35 cling to each other sufficiently to provide a batt which may be moved about without falling to pieces. For this reason, a suitable binding material must be used.

Experience has taught that in order to obtain 40 the desired results, the binding material must be more evenly distributed upon the surfaces of the individual fibers before they have had an opportunity to combine in bunches, and best practice indicates that the binding material should be applied to the blast of steam and molten material 45 before it enters the settling chamber.

The oldest and most widely used method is that of simply permitting the binding material to drop or pour directly upon the blast before it enters the settling chamber. This method, however, 50 has numerous disadvantages, one of them being that the rate of flow of the material is not dependable when applied in this manner. One reason for this is that the character of the binding material is such that it tends to stick to the in- 55 side walls of the pipe through which it flows and

almost invariably prevents the proper functioning of any valves which may be used to regulate and control its flow.

Another disadvantage found in using this method is that the binding material is not atomized before it falls upon the blast, and consequently falls upon only one portion of the blast in such a manner that it does not become evenly distributed on the forming fibers.

Heretofore, numerous other methods have been 10 devised to achieve the even distribution necessary to the proper production of mineral wool batts, but, insofar as applicants are aware, all of these methods leave much to be desired.

The chief object of our invention is to provide 15 means whereby any suitable binding material may be evenly distributed on the surfaces of the individual fibers before they become deposited on the base of the settling chamber.

Another object is to provide apparatus whereby 20 two or more fluids may be so applied that a film or coating of binding material will be evenly precipitated, formed, or deposited on the surface of each individual fiber before it is incorporated into the batt.

A still further object is the provision of means 25 whereby the binding materials may be discharged into the settling chamber under ideal conditions for distribution on the mineral wool fibers.

A further object is the provision of apparatus 30 whereby both the temperature and the rate of flow of the binding material may be controlled as desired.

The full nature of our invention and its other 35 objects and advantages will be understood from the accompanying drawing and the following description and claims.

The drawing is a side elevational and partly 40 sectional view of a cupola and a blow chamber of a mineral wool plant having one of many embodiments of our invention operatively associated therewith.

In carrying out our invention we make use 45 of any suitable cupola 1, blast means 2, and a blow chamber 3, which are operatively associated together for the production of mineral wool batts.

The mineral wool is produced by melting wool rock, or slag, in the cupola 1 with coke or gas, and pouring the molten material in a stream 4 which is subjected to the action of a shredding steam blast 5 which issues from a nozzle 6 of the steam blast means 2.

The above described apparatus for producing 55 the untreated mineral wool is, of course, old, the entire novelty of our invention residing in our

binding material substances before they pass through the blowers, as these substances atomize more readily when they are first mixed in a wet-heated gas. The steam also prevents the cementitious substances from drying in the hot products of combustion, and, to a certain extent, prevents their adhering to the conduits 10 and 11 and the blowers 12 and 13.

The steam blast 5 carrying the molten shredded material and the atomized binding material, if desired, may be shielded by a tubular guide means 33 which preferably extends substantially as shown into the blow chamber 3. This guide means not only restricts the admission of cool air into the blow chamber, but protects the operation from any molten particles which might otherwise strike and rebound from the rear wall 34 of the blow chamber 3.

It will be observed, by referring to the accompanying drawing, that the pressure gauges 31 and 32 are placed immediately above the blowers 12 and 13, where they can be readily observed by the cupola operator. These gauges indicate the amount of the steam or heated gas which is being mixed with the binding materials.

The rate of flow of the binding material substances is, of course, proportional to the speed of the pumps, which may be ascertained in any suitable manner, such as, for instance, by noting the position of the control means on the variable speed transmission (not shown) which is old in the art and requires no detailed description.

In view of the above, it will be seen that the several objects of the invention are achieved and other advantageous results are attained.

As many changes could be made in carrying out the above description without deviating from the scope of our invention, it is intended that all matter incorporated in the above description, or shown in the accompanying drawing, shall be interpreted as illustrative, and not in a limiting sense.

We claim:

1. An organization for first heating and thereafter applying liquid adhesive materials to a stream of newly formed fibers consisting of mineral materials shredded in a molten condition by 5 a fluid blast directed against a stream of said molten mineral materials, said organization including an adhesive supply system, a steam supply system, and a gaseous products of combustion supply system, all of said systems having at 10 least one common discharge conduit.

2. An organization for first heating and thereafter applying liquid adhesive materials to a stream of newly formed fibers consisting of mineral material shredded in a molten condition by 15 a fluid blast directed against a stream of said molten mineral materials, said organization including an adhesive supply system, a steam supply system, and a gaseous products of combustion supply system, all of said systems being provided with at least one common discharge conduit, said adhesive supply system including a plurality of liquid adhesive reservoirs and pumping means operatively connected to said reservoirs and said common discharge conduit. 25

3. An organization for first heating and thereafter applying liquid adhesive materials to a stream of newly formed fibers consisting of mineral materials shredded in a molten condition by 30 a fluid blast directed against a stream of said molten mineral materials, said organization including an adhesive supply system, a steam supply system, and a gaseous products of combustion supply system, all of said systems being provided with at least two common discharge conduits, said adhesive supply system having a plurality of liquid adhesive reservoirs and pumping means connected to said reservoirs and said discharge conduits. 35
